CLEANSING ARTICLE

George W. Brooks, La Grange, Ill., assignor to
The S. O. S. Company, Chicago, Ill., a corpora-
tion of Delaware

Original application February 10, 1936, Serial
No. 63,133, now Patent No. 2,079,600, dated May
11, 1937. Divided and this application April 9,
1937, Serial No. 135,841

2 Claims. (Cl. 15—122)

The present invention relates to the art of
cleansing articles.

Among the objects of the invention is to provide
a novel cleansing article of the type composed of
5 a mass of metallic fibres or filaments and soap.

In the use of cleansing articles composed of
metal fibres, usually designated "steel wool"
although the fibres may be of any metal desired
10 or even of non-metallic substance but having the
physical characteristics of metal fibres, and a
distribution of soap throughout the fibrous mass
and adhering to or held therein by the fibres, the
15 soap component becomes used up when the metal-
lic wool part has been only partly used up.

15 The present invention comprehends as a novel
feature thereof a double distribution of soap in
the wool mass with a double interspersion of voids
affording access of water to the soap, the soap of
20 one distribution being in the outer portion of the
wool mass and near and at the working surface
thereof to act as an immediate or primary supply
of soap, and the soap of the other distribution
25 being located within the wool mass to act as a
reservoir or secondary supply of soap for the
primary supply surrounding it.

The preferred embodiment of the invention
comprises a pad or body of metal wool fibres and
30 soap of different characteristics distributed
throughout the extent of the metal wool pad or
body in two distinct portions of the pad or body.
The inner portion of the pad or body is provided
35 with a soap distribution having a slower rate of
dissolving than that of the outer portion, and said
outer portion wholly incloses said inner portion,
the greater part of the soap in each portion being
40 in the form of coatings about most of the fibres
and so arranged as to provide spaces or voids
between and among the coated fibres. The coat-
ings in the inner portion may be of substantially
45 the same thickness or thinner than, or even
thicker than, the coatings of the outer portion.
So far as weight or volume may be concerned,
there may be an equal, lesser, or greater amount
50 of the soap in the inner portion, yet, it is of such a
chemical nature as to dissolve more slowly than
the soap of the outer portion, thereby acting as a
reserve supply for the outer portion of the pad or
body.

55 Other objects, capabilities, advantages, features
and the like are comprehended by the invention
as will later appear and as are inherently posses-
sed by the invention.

In the drawing:

Fig. 1 is a horizontal sectional view taken in a

plane represented by line 1—1 in Fig. 2 of the
drawing;

Fig. 2 is a vertical sectional view taken in a
plane represented by line 2—2 in Fig. 1 of the
drawing;

Fig. 3 is a fragmentary sectional view on a
greatly enlarged scale showing the difference
between the soap portions and voids in the sec-
ondary and primary supplies or distributions.

Referring more in detail to the drawing, the 10
various embodiments of my invention are shown
in the conventional form of a pad of compressed
metal wool or filaments and soap associated
therewith, as agglutinated thereto or held there-
by, the product having a texture or skeletal struc- 15
ture, somewhat like a sponge, with innumerable
interspersed voids 1 and 1^a, the soap 3^a concen-
trated in the inner portion being of different
character or chemical nature than the soap 3 in
the outer portion of the article, the metal wool 20
filaments 2 acting as the supporting or reinforc-
ing means with which the soap 3 and 3^a has
become associated.

The association of the soap with the metal wool
fibres or filaments does not appear to be regular 25
but seems to be in the form of coatings 3 and 3^a.
The soap may so agglutinate or coalesce as to
adhere or cling to two or more filaments or may
break away from said filaments and thus appear
to be suspended or held between or among two or 30
more metal wool fibres or filaments. The form
of these associated coatings are varied, in some
cases seeming to be filmy, in others filamentous,
and others granular. These concentrated coat-
ings are small and in this invention are not 35
greater in size than grains of wheat or rice or the
like. These soap coatings assist in protecting the
metal wool filaments from rusting or corroding or
the like.

In use the article is wetted with water so that
the water will permeate through the voids or part
of them so as to dissolve some of the soap, particu-
larly the coatings 3 to form a soap solution and
suds. The article is then applied to the surface
of the object to be cleansed, only a part of the 45
coatings 3 dissolving and being used up, the metal
fibres or filaments functioning to mechanically
cut or scrape the dirt and the like to be removed.
As the primary soap coatings 3 become dissolved
and used up some of the soap coatings 3^a will be 50
softened by the water and will feed into the adjac-
ent portion of the wool mass and agglutinate, on
drying, to the filaments thereof to gradually
replace or replenish the soap coatings already
dissolved and used up. In this way the pad has 55

a longer life so that by the time the soap in the secondary supply or distribution becomes exhausted or used up, the wool mass also has become used up.

5 The advantages of the invention will be readily apparent to those skilled in the art to which the invention belongs. An important advantage is that it furnishes soap in a readily dissolvable form as contrasted with a cake of soap or a plurality of chunks of soap, and at the same time provides a flexible or yieldable pad.

10 This is a division of my copending application Serial No. 63,133, filed February 10, 1936, for Cleansing article, which issued May 11, 1937, as 15 Patent No. 2,079,600.

15 Having thus explained the nature of the invention and described an operative manner of constructing and using the same, although without attempting to set forth all of the forms in which 20 it may be made, or all of the forms of its use, what is claimed is:

20 1. A combined metal wool and soap cleaning pad comprising a body of metal wool with soap distributed throughout its extent in two distinct 25 portions, one portion entirely inclosing and surrounding the other portion to provide an inner and

an outer portion, most of the soap in each portion being in the form of coatings about substantially all of the fibres of the metal wool and providing voids among the coated fibres, the soap coatings of the inner portion being of such different character from the soap coatings of the outer portion as to provide an inner soap distribution having a slower rate of dissolving and hence forming a reserve soap supply for the outer portion of the pad. 5

2. A combined metal wool and soap cleaning pad comprising a body of metal wool with soap distributed throughout its extent in two distinct portions, one portion entirely inclosing and surrounding the other portion to provide an inner 10 and an outer portion, most of the soap in each portion being in the form of coatings about substantially all of the fibres of the metal wool and providing voids among the coated fibres, the soap coatings of the inner portion being of such different 15 chemical character from the soap coatings of the outer portion as to provide an inner soap distribution having a slower rate of dissolving and hence forming a reserve soap supply for the outer 20 portion of the pad. 25

GEORGE W. BROOKS.
